UNITED STATES PATENT OFFICE

157,252

DOG MUZZLE OR SIMILAR ARTICLE

Hermine Goldberg, Omaha, Nebr., assignor of one-half to Ralph D. Goldberg, Omaha, Nebr.

Application March 13, 1948, Serial No. 145,063

Term of patent 14 years

(Cl. D38—6)

To all whom it may concern:

Be it known that I, Hermine Goldberg, a citizen of the United States and a resident of Omaha, in the county of Douglas and State of Nebraska, have invented a new, original, and ornamental Design for a Dog Muzzle or Similar Article of which the following is a specification, reference being had to the accompanying drawing, forming part thereof.

Figure 1 is a side elevation of a dog muzzle or similar article showing my new design, this being the left side and the right side being substantially similar thereto, and

Figure 2 is a perspective view thereof with the parts arranged as they would be when the muzzle is placed on the animal.

I claim:

The ornamental design for a dog muzzle or similar article, substantially as shown and described.

HERMINE GOLDBERG.
